REFRIGERATOR AND FREEZER DOOR
CONSTRUCTION

Howard J. Tenniswood, Adrian, Mich., assignor to Revco,
Inc., Deerfield, Mich., a corporation of Michigan
Filed Sept. 29, 1958, Ser. No. 764,061
8 Claims. (Cl. 20—35)

The cabinets of household food freezers formerly were boxes with top opening doors. The boxes and doors both were heavily insulated. The freezers usually were installed in basements or other out of the way places. They usually were packed with meat and other perishable foods which their owners obtained in large quantities and stored in the freezers to be used over weeks or months of time. In the construction of the insulated boxes and top opening insulated doors much attention was given to insure maximum prevention of ingress of heat. Little attention was given to convenience in use and very little attention was given to attractive appearance.

In recent years, in the construction, merchandizing and utilization of freezers and refrigerators more emphasis was directed to convenience in use and attractive appearance. It became the practice to incorporate freezers with front opening doors in the same cabinets with portable, or "free standing," refrigerators. This practice became general in urban areas where foods were acquired in smaller quantities and greater varieties and were kept frozen by householders for shorter periods.

The present trend is strongly toward building refrigerators and freezers into the convenient and often beautiful cabinet work and paneling with which modern kitchens are lined. Building a freezer and a refrigerator into a general scheme of kitchen wall cabinets and panels has many advantages. It enables the freezer and the refrigerator each to be placed in its most convenient location independently of the other. Each can be at such height that its contents are visible and accessible without stooping or stretching. The refrigerating and freezing mechanism can be left out of the interior of the cabinets, thus providing more space for food and leaving the food space susceptible of better arrangement. The refrigerating or freezing mechanism when installed above or at the side of a built-in refrigerating or freezing cabinet can be easily and economically serviced or replaced. The built-in refrigerator and freezer do not stand out into the room, to be dodged around and cleaned around. If the doors are custom-built, or the other paneling is custom-built at the place of installation, the material of the doors and the material of the other cabinet work can be made to match or harmonize. Custom-built refrigerator doors and freezer doors are expensive, however.

It is an object of this invention to provide a basic refrigerator or freezer door core and interior functional liner in combination with invertible and interchangeable accessories which can be readily assembled with the core to make a large variety of right or left hand doors that differ in appearance and in aesthetic characteristics.

Another object is to make it possible to produce standard factory-built refrigerators and freezers having the advantages of custom-built refrigerators and freezers, at much lower manufacturing cost.

And still another object is to make it possible for distributors and dealers with a small investment in inventory to satisfy the various preferences of customers.

Other objects and numerous advantages of the invention will become apparent upon perusal of the following description as illustrated by the accompanying drawings, in which:

FIG. I is a fragmentary sectional view through the

2

swingable edge of one form of a door constructed in accordance with the instant invention;

FIG. II is a view of a temperature equalizing panel employed in the form of door shown in FIG. I, a trim edging being shown as partially removed from the temperature equalizing panel; and

FIG. III is an elevational view of the core of a refrigerator or freezer door, a fragment of which is shown in FIG. I, the door frame which normally surrounds the door core being shown as partially removed.

The insulating freezer or refrigerator door incorporating the instant invention, in the form disclosed herein, comprises a core 1 that is square as seen in front elevation, though the core may be of any desired shape so long as the front face is symmetrical about vertical and horizontal axes. The core 1 comprises an inner shell member 2, which may be of metal or plastic, either flat or molded or pressed into any preferred shape, and an outer shell member 3 which also may be of metal or plastic material and may be molded or pressed into any preferred shape. In the form of device shown, the outer shell member 3 is flat with an offset margin 4.

A door frame 5, which has a channel-like cross section and as shown in FIG. III is square in elevation when assembled, surrounds the inner and outer shells 2 and 3 to form an enclosure that is filled with thermo-insulating material of any desired type. Expandable polystyrene insulating material has been found to be efficient and otherwise suitable. The insulating material known in the trade as expandable polystyrene consists of hard elastic pellets. Similar rigid type insulating material of urethane also is available.

As shown in FIG. I, the inner flange of the door frame 5 is surrounded by a flexible gasket. The form of gasket shown in FIG. I is fully described in a copending application and is not a feature of the instant invention, since other forms of gaskets may be employed.

Secured by screws to one side of the door frame 5 are webs 7 forming part of a door pull 6 comprising a handle 8, the structure of the door pull being such that it can be secured to the frame 5 only, without interfering with any other part of the door structure. The other side of the door frame 5 is provided with reinforcing strips 9 and 10 that are threaded to receive screws 11 for attaching hinges 12 and 13 to the door frame, thus securing the hinges to the door frame only without interfering with any other part of the door structure.

The side of the door frame 5 which carries the reinforcing strip 10 is severed over the strip, the strip being secured by welding or otherwise to the door frame on one side only of the dividing cut. When the two sides of the dividing cut are brought together and the screws 11 are screwed into the plate on one side or both sides of the dividing cut to fasten the hinge 13 to the frame 5, the frame closely embraces the shell member 3 and cannot be removed therefrom without taking out the screws 11.

When, however, the screws 11 are backed out and the hinge 13 is removed, the door frame 5 can be sprung open, as indicated in FIG. III, until the door frame can be swung out of parallelism with the core 1 and removed from the core. After removal from the core the door frame 5 can be turned over and replaced upon the core 1 with the door pull on the right side instead of the left side. The hinge 13 then can be replaced on the left side. The door thus can be converted from a right hand opening door to a left hand opening door.

It sometimes happens that cold spots develop on outer shell members of freezer and refrigerator doors, and when the relative humidity of the room air is high moisture from the air is liable to condense on the cold spots and detract from the appearance of the door or even

3

cause the householder to think that the freezer is not functioning properly. Under some conditions the condensation is so copious that water of condensation runs down the face of the door and drips from its lower edge. If the outer shell of such a freezer door is covered with an ornamental panel, heat may flow directly from spots on the panel to the cold spots in the outer shell of the door, thus causing cold spots to form on the ornamental panel. Even when an ornamental panel is spaced from the outer shell of a freezer door, heat may radiate from spots on the ornamental panel across the air space to the cold spots on the outer shell until cold spots form on the ornamental panel. Efforts have been made to avoid the formation of cold spots on ornamental panels by interposing layers of insulating material such as porous fiber board between the outer shell of the door core and the ornamental panel, but even in such cases heat flows through the insulating material or board from the ornamental panel to the cold spots on the shell member, causing wet spots to appear on the ornamental panel.

In the device of my invention such spotting of ornamental panels is minimized or avoided by interposing a temperature equalizer between the ornamental panel 14 and the shell 3. The temperature equalizer consists of a sheet of a heat conductive metal 15 which lies in direct contact with the ornamental panel 14 but is spaced from the shell 3. The thermo-conductive sheet 15 is reinforced at its edges by turned-over strips 16, and is held away from the shell 3 by spacing nubbins 17. The nubbins 17 can be punched from the metal of the temperature equalizer sheet 15 as shown in the drawings, or they can be composed of thermo-insulating material.

Employing a sheet of thermo-conductive metal to prevent heat from flowing directly from spots on the ornamental panel 14 to spots on the shell 3 may appear to be a rather paradoxical way of accomplishing the purpose. It accomplishes the purpose, however, not by blocking the flow of heat but by taking from a large area of the ornamental panel 14 heat which otherwise would be abstracted from a definite spot. The total heat loss from the entire ornamental panel may be no less than it would have been in the absence of the temperature equalizer sheet 15, but the equalizer sheet tends to get from the entire area of the ornamental panel the heat which it radiates to superchilled places on the outer shell 3. It thus prevents the temperature of any spot of the ornamental panel 14 from being reduced sufficiently to cause sweating.

The ornamental panels 14 are capable of being selectively subassembled with the heat equalizer sheet by means of a trim edging 18 as shown in FIG. I. The trim edging 18 is formed with an outer C-shaped portion 19 and an inner bead 20 which resiliently grip the edge of the ornamental panel 14 and the edge of the temperature equalizer sheet 15. When the C-shaped portion 19 and the bead 20 are sprung into gripping engagement with the edge of the ornamental panel 14 and the reinforcing strip 16 of the sheet 15, they hold the panel 14 and the temperature equalizer sheet 15 firmly together.

The trim edging 18 has a flange 21 that extends inwardly beyond the bead 20. Projecting backwardly through the flange 21 are snap fasteners 22 which, to secure the ornamental panel 14 and heat equalizer sheet 15 to the core 1, are forced into registering openings 23 in the door frame 5 and the outer shell member 3. Each of the snap fasteners 22 has a head 25 which lies between the flange 21 of the trim edging 18 and the reinforcing strip 16 of the heat equalizer sheet 15. The snap fasteners 22 have bowed resilient prongs 26 which are squeezed toward each other as the fasteners are forced through the registering openings 23, and which spring outwardly after the bowed portions of the prongs have passed inwardly through the registering openings.

To remove the ornamental panel 14 and the heat equalizer sheet 15, a screw driver may be inserted be-

tween the door frame 5 and the trim edging 18. The ornamental panel and heat equalizer sheet subassembly thus may be pried away from the door core at several places by pulling out the snap fasteners 22. As shown in FIG. II, the trim edging 18 is severed and can be opened to permit the substitution of a different ornamental panel. The subassembly then can be replaced upon the door core by again pushing the snap fasteners 22 into the registering openings 23.

It is apparent from the foregoing disclosure that the purpose and objects of the instant invention are achieved in the preferred form disclosed. It is to be understood that the form described herein and illustrated by the accompanying drawings is exemplary only in that the invention includes other forms and modifications which are within the spirit and scope of this invention.

I claim:

1. In a door for an insulated cabinet, in combination; a door core having an outer shell; an ornamental panel; a heat equalizer sheet of thermo-conductive material; means mounting said ornamental panel in juxtaposition with said equalizer sheet on said door core; and a plurality of nubbins holding said heat equalizer sheet spaced from said outer shell.

2. In a door for an insulated cabinet, in combination; a door core having an outer shell; an ornamental panel; a heat equalizer sheet of thermo-conductive material; means mounting said ornamental panel in juxtaposition with said equalizer sheet on said door core; and a plurality of nubbins holding said heat equalizer sheet spaced from said outer shell; said mounting means comprising a resilient edging trim having a C-shaped portion and a bead which is sprung over the edges of said ornamental panel and said equalizer sheet to hold them in a subassembly.

3. In a door for an insulated cabinet, in combination; a door core having an outer shell; an ornamental panel; a heat equalizer sheet of thermo-conductive material; means mounting said ornamental panel in juxtaposition with said equalizer sheet on said door core; and a plurality of nubbins holding said heat equalizer sheet spaced from said outer shell; said mounting means comprising a resilient edging trim having a C-shaped portion and a bead which is sprung over the edges of said ornamental panel and said equalizer sheet to hold them in a subassembly; said edging trim having a flange carrying fasteners to releasably secure said flange to said door core.

4. In a door for an insulated cabinet, in combination; a door core having an outer shell; an ornamental panel; a heat equalizer sheet of thermo-conductive material; means mounting said ornamental panel in juxtaposition with said equalizer sheet on said door core; and a plurality of nubbins holding said heat equalizer sheet spaced from said outer shell; said mounting means comprising an edging trim which is forced over the edges of said ornamental panel and said equalizer sheet to hold them in a subassembly and snap fasteners for holding said subassembly to said door core.

5. In a door for an insulated cabinet, in combination; a door core consisting of an inner shell member and an outer shell member; a door frame, channel-shaped in cross section; said shell members and said door frame having a front elevation which is symmetrical about vertical and horizontal axes; said door frame adapted to perimetrical surround said shell members; said door frame having a dividing cut on its perimeter to enable assembly around said shell members; removable securing means for bringing together and securing said dividing cut; said inner and outer shell members and said door frame when assembled forming an enclosure for insulating material; said door frame having a door pull attached to one side thereof and hinges attached to its other side; said door frame upon removal of said securing means being separable from said shell members and when so separated and reassembled in an inverted position with

respect to said shell members changing a right hand opening door to a left hand opening door and vice versa.

6. In a door for an insulated cabinet, in combination; a door core consisting of an inner shell member and an outer shell member; a door frame adapted to perimetricaly surround said shell members; said door frame having a dividing cut on its perimeter to enable assembly around said shell member; removable securing means for bringing together and securing said dividing cut; said inner and outer shell members and said door frame when assembled forming an enclosure for insulating material; said door frame having a door pull attached to one side thereof and hinges attached to its other side; said door frame upon removal of said securing means being separable from said shell members and when so separated and reassembled in an inverted position with respect to said shell members changing a right hand opening door to a left hand opening door and vice versa; an ornamental panel; a heat equalizer sheet of thermal-conductive metal; means mounting said ornamental panel in juxtaposition with said heat equalizing sheet on said door core; and a plurality of nubbins holding said heat equalizer sheet spaced from said outer shell member.

7. In a door for an insulated cabinet, in combination; a door core consisting of an inner shell member and an outer shell member; a door frame adapted to perimetricaly surround said shell members; said door frame having a dividing cut on its perimeter to enable assembly around said shell member; removable securing means for bringing together and securing said dividing cut; said inner and outer shell members and said door frame when assembled forming an enclosure for insulating material; said door frame having a door pull attached to one side thereof and hinges attached to its other side; said door frame upon removal of said securing means being separable from said shell members and when so separated and reassembled in an inverted position with respect to said shell members changing a right hand opening door to a left hand opening door and vice versa; and ornamental panel; a heat equalizer sheet of thermal-conductive metal; means mounting said ornamental panel in juxtaposition with said heat equalizer sheet on said door core; and a plurality of nubbins holding said heat equalizer

sheet spaced from said outer shell member; said mounting means comprising a resilient edging trim having a C-shaped portion and a bead which is sprung over the edges of said ornamental panel and said heat equalizer sheet to hold them in a subassembly.

8. In a door for an insulated cabinet, in combination; a door core consisting of an inner shell member and an outer shell member; a door frame adapted to perimetricaly surround said shell members; said door frame having a dividing cut on its perimeter to enable assembly around said shell members; removable securing means for bringing together and securing said dividing cut; said inner and outer shell members and said door frame when assembled forming an enclosure for insulating materials; said door frame having a door pull attached to one side thereof and hinges attached to its other side; said door frame upon removal of said securing means being separable from said shell members and when so separated and reassembled in an inverted position with respect to said shell members changing a right hand opening door to a left hand opening door and vice versa; and ornamental panel; a heat equalizer sheet of thermal-conductive metal; means mounting said ornamental panel in juxtaposition with said heat equalizer sheet on said door core; and a plurality of nubbins holding said heat equalizer sheet spaced from said outer shell member; said mounting means comprising a resilient edging trim having a C-shaped portion and a bead which is sprung over the edges of said ornamental panel and said heat equalizer sheet to hold them in a subassembly; said edging trim having a flange carrying fasteners to releasably secure said flange to said door core.
